UNITED STATES PATENT OFFICE.

SIMON GOLDNER, OF NEW YORK, N. Y.

MANTLE FOR INCANDESCENT LIGHTING.

SPECIFICATION forming part of Letters Patent No. 634,815, dated October 10, 1899.

Application filed May 25, 1899. Serial No. 718,175. (No model.)

To all whom it may concern:

Be it known that I, SIMON GOLDNER, a subject of the King of Roumania, residing at New York, borough of Manhattan, in the county 5 and State of New York, have invented new and useful Improvements in Mantles for Incandescent Lighting, of which the following is a specification.

These mantles, called "incandescent" mantles for short, as known are quite frail and apt 10 to break or crumble, and by means of this invention the mantle can be reinforced or strengthened, as set forth in the following specification and claims and illustrated in the 15 annexed drawings, in which—

Figure 1 is an elevation of the mantle. Fig. 2 is a transverse section of Fig. 1.

An incandescent mantle is shown provided 20 with a reinforcement which tends to make such mantle more durable and prevent shattering of the same from vibrations.

These mantles generally break at the bulging portion below the neck. This neck portion of mantle 1 has the usual loop 2 for attaching to a rod or support. About this loop 25 2 is coiled or connected a thin wire 3—such, for example, as platinum. After being secured to loop 2 this wire or filament 3 leads into the mantle, preferably centrally, forming the stem 4, and at a suitable distance has a 30 number of lateral or radiating arms 5, attached to ring 6, the latter sitting snugly against the interior of the mantle. From the ring 6 depend a number or series of wires 7. The bottom edge of the mantle is provided 35 with a tape or string 8, such strip 8 being pasted or secured round about such edge portion, and the depending wires 7 being curved at their lower ends such curved portions can 40 be made to sit about the bottom edge of the mantle and clasp the strip or tape 8. The extra piece or string 8 at the bottom edge is practically made of incombustible material, such as asbestos. Such piece or reinforce- 45 ment 8 tends to hold the mantle in shape, and the series of lower wires 7 being bent or clasped about the cord or edge 8 support the lower part of the mantle to relieve the strain

on the neck or upper part of such mantle. Any suitable number of wires can be used for 50 the series 7. Four such wires have been found in practice to be satisfactory. A single wire 4 at the upper part in the mantle has been found sufficient and gives a light structure. The ring 6 in the mantle or in the 55 lower mantle portion tends to hold the mantle in cylindrical or proper form and such wire 6 or series 5, when made to rest on a burner, tends to support the mantle against breakage, besides relieving the upper part of 60 the mantle from weight or strain.

What I claim as new, and desire to secure by Letters Patent, is—

1. A mantle having a loop at its upper end, a wire suspended centrally within the mantle 65 from said loop, a ring arranged in the mantle and suspended from said wire, and vertical wires depending from said ring and engaging the lower end of the mantle, substantially as described.

2. A mantle having a loop at its upper end, a wire suspended centrally within the mantle from said loop, a ring arranged in the mantle and suspended from said wire at a point intermediate the top and bottom of the mantle 75 whereby the mantle is held distended, and vertical wires depending from said ring and having hook-shaped lower ends engaging the lower edge of the mantle, substantially as described.

3. A mantle having a loop at its upper end and a reinforcing-tape at its lower edge, a wire suspended centrally within the mantle from said loop, a ring arranged in the mantle and suspended from said wire, and a plurality of wires depending from said ring and having hooked lower ends engaging the lower edge of the mantle and said reinforcing-tape, substantially as described.

In testimony whereof I have hereunto set 90 my hand in the presence of two subscribing witnesses.

SIMON GOLDNER.
